UNITED STATES PATENT OFFICE

JOHN W. COOK, OF TOPEKA, KANSAS

TELEPHONE AND TELEGRAPH CIRCUITS

Application filed April 8, 1925. Serial No. 21,486.

My invention relates to multiplex telegraph and telephone circuits or apparatus for transmitting and receiving telephone or telegraph messages or signals over two untransposed or two transposed telegraph wires, either one of which may be iron or copper, or both copper, or both iron, without interfering with existing circuits, which may be printer, duplex or quadruplex telegraph circuits.

One object of my invention consists in providing a circuit or apparatus whereby use may be made of existing telephone lines,—whether metallic or grounded,—or of power transmission lines, for transmitting and receiving telephone messages or for telegraph transmission without interfering with the existing circuits.

A further object of my invention is to provide apparatus or a circuit whereby transmission and reception of telephone or telegraph messages is possible either over a telephone metallic line as one side of a pair while employing a printer, duplex or quadruplex telegraph wire as the other side of the pair; or over a combination of telegraph and telephone wires, without interfering with the existing circuits.

Another object of my invention consists in providing a circuit or apparatus adapted to balance out such interference in the receiving apparatus as would ordinarily be experienced from ten or more quadruplex sets being operated on the same table with the receiving apparatus.

The foregoing enumerated objects and advantages of my invention, as well as other advantages inherent in the invention, will all be more fully understood and comprehended from the following detailed description of the accompanying drawings, wherein the circuits and apparatus are diagrammatically illustrated.

Figure 1 is a diagram showing a telegraph and a telephone circuit embodying my invention.

Figure 2 is a diagram showing the combination of a telegraph and telephone circuit and a telegraph circuit.

Figure 3 is a diagram illustrating my in-

vention connected to four telegraph circuits; two of the circuits being connected at their terminals to the other two telegraph circuits forming the two sides of a metallic circuit for my apparatus.

Figure 4 is a diagram illustrating my invention as merely applied to a telegraph wire.

Figure 5 is a diagram illustrating two transmitting and two receiving sets of my apparatus connected at each end of two telegraph wires.

In the exemplifications of the invention as shown in the drawings, beginning with Figure 1, 10 represents a telegraph wire, in quadruplex service, provided with air choke coils at 11, 11, leading to the telegraph apparatus indicated at 12, 12. 13 represents a metallic telephone simplex circuit, which is provided with the simplex coils 14, 14, 14, 14; a number of fixed condensers arranged in pairs as shown at 15; selectors and telephone bridges across the lines 13, as shown at 16, and telegraph apparatus indicated at the ends of the lines and beyond the simplex coils 14, as shown at 12. The small capacity condensers shown at 15 are connected at an intermediate point, by lines 17, as a tap for the high frequency transmitting and receiving apparatus which are schematically indicated at 18, 18; the apparatus being also shown connected with the single telegraph wire 10 by means of wires 19, 19. The condensers referred to are of such capacity as not to interfere with telephone transmission on existing lines; while the connections to the high frequency transmitting and receiving apparatus 18, 18, which are balanced to both sides of the telephone line, cause no interference from the multiplex apparatus to the telephone lines; while on the other hand a circuit of least resistance to the multiplex circuit is provided on account of employing two wires instead of one.

The air choke coils 11 are connected in series with the quadruplex sets or telegraph apparatus for the purpose of smoothing out high battery impulses in the receiving apparatus of the multiplex circuit caused by the changing long and short ends of the quadruplex battery.

In Figure 2, which illustrates a combination of telegraph and telephone circuits and a telegraph circuit,—adapted to send and receive telephone messages or for telegraph transmission over a telephone metallic line as one side of a pair, while using either a printer, duplex or quadruplex telegraph wire as the other side of the pair of lines; or to be employed as a combination of telegraph and telephone wires without interfering with existing circuits,—the circuit comprises a telegraph wire 10, in quadruplex service, provided with the air choke coils 11, 11, leading to the telegraph instruments or apparatus indicated at 12, 12. One end of line 10 is shown connected to the high frequency transmitting and receiving apparatus 18, while the other end is shown connected with the adjacent high frequency transmitting and receiving apparatus 18 by the wire 20. The line 10 constitutes one side of the circuit; while 21 represents a single Morse service; and 13 represents a metallic telephone circuit in dispatcher's service. The lines 13 and 21, connected at their terminals, constitute the other side of the circuit. The telephone wires 13 are provided with the simplex coils 14 to which the telegraph apparatus 12 are connected; and the telephone line is shown provided at 16 with selectors and telephone bridges across the lines; and also with fixed condensers 15. The small capacity condensers 15 at one end of the telephone lines are connected at an intermediate point by means of wire 22 with telegraph line 21 and with an air choke coil 11 which in turn is connected with a telegraph apparatus 12.

The other end of telegraph line 21 is connected with a wire 23 which, at one end, is provided with an air choke coil 11 and is connected to a telegraph apparatus 12; while the other end of wire 23 is connected with the high frequency transmitting and receiving apparatus shown at 18. At the opposite end of the telephone lines, the small capacity condensers 15 are connected at an intermediate point, by means of wire 17, with the adjacent high frequency transmitting and receiving apparatus 18.

In Figure 3 I show a diagram of high frequency transmitting and receiving apparatus shown at 18, connected to two untransposed lines in telegraph service and comprising the wires 24, 25, 26 and 27 in quadruplex telegraph service between two terminals; the two wires 24 and 25 being connected at their adjacent ends through a small fixed condenser 28; while the two wires 26 and 27 are connected at their adjacent ends through the small fixed condenser 29. The wires 24, 25, 26 and 27 in advance of their connections with the condensers 28 and 29 and at opposite ends are each provided with the air choke coils 11, which in turn are connected in series

with the telegraph keys or instruments indicated at 12.

In Figure 4, I illustrate a single telegraph wire 10 for quadruplex or duplex service; the high frequency apparatus bridge being represented at 18, which are bridged between the line and ground at both ends of the line, as shown at 30. The ends of the line are also provided with air choke coils 11, in series with the telegraph keys or instruments 12.

Figure 5 diagrammatically illustrates two multiplex telephone circuits connected over the same line wires indicated at 31, 32, regardless whether they are telephone or telegraph wires or circuits; the apparatus being hooked up the same whether the wires are both telegraph or both telephone wires; the figure showing more than one set on the same line, as for example 18 designates the high frequency transmitter of one circuit; 18^a indicating the high frequency receiver at the distant end of the circuit; while 18 is the high frequency transmitter of another circuit and 18^a is the high frequency receiver at the distant end of the last mentioned circuit. It is, of course, apparent that any desired number of sets (as shown) may be involved and that they would be connected to the line wires in similar manner and that there would be no interference between the different multiplex circuits; the circuits comprising air choke coils 11 arranged in series with the telegraph keys or instruments indicated at 12.

In order to accomplish the various objects and advantages heretofore set forth, use is made of oscillations or electromagnetic waves of high frequency which are transmitted over the wires; the frequencies, in tests that have been made, being above audibility.

In practice, I have made use of a metallic telephone line as one side of a pair of my circuit, by shunting the metallic telephone line with a number of small capacity condensers, as for example two, arranged in series and connecting the centers of the condensers direct to a telegraph wire, and using a telegraph wire as the other side of the pair of lines of the circuit; Figure 1 illustrating the multiplex apparatus bridged across a telegraph wire and a metallic telephone circuit.

In a test made over a circuit of a considerable distance, one side of the circuit consisted of Number 9 copper wire in quadruplex service, while the other side of the circuit was a single Morse Number 9 copper wire and a metallic dispatcher's telephone line of Number 9 copper wire, with connections arranged as shown in Figure 2. The reception over these mixed telephone and telegraph wires was without interference either to the multiplex circuit or to the circuits being worked over, and reception was equivalent to ten standard transmission units.

As is well known, it has been impossible to

obtain satisfactory telephone transmission over two untransposed wires employed in telegraph service, either at voice frequencies or at the higher frequencies, due to inductive disturbances from the wires connected to and from adjoining wires. A telephone receiver connected between two quadruplex telegraph wires, resulted in a great disturbance in the receiver, caused by leakage between the two 5 telegraph wires and electro-magnetic and electro-static disturbances from adjacent wires; the disturbances in the receiver being much greater if the two telegraph wires are spaced farther apart on the pole lines. On 10 the other hand, in tests with my apparatus, reception was without interruption when the set was connected either between adjacent wires on the same arm or between a wire on one arm and a wire on another arm. If more 15 than one circuit is to be connected to the same line wires, the connections for the apparatus of different circuits may be to the same point on the line.

The modulated high frequency current is 20 impressed on the lines which are connected as shown in Figures 1, 2, 3, 4 and 5, which illustrate the different combinations of untransposed wires with which connection is made and the use of air choke coils and condensers, 25 by means of which the modulated high frequency currents are conducted over the wires without interfering with existing circuits.

Referring to Figure 3, 24 is a wire in quadruplex service connected to the wire 25 by 30 the small condenser 28. This forms one side of a circuit for multiplex operation.

Wires 26 and 27 are also connected by a 35 small condenser 29 and form the other side of the multiplex circuit. The quadruplex apparatus is connected through the air choke 40 coils represented at 11. These coils 11 smooth out the heavy battery impulses from the high frequency apparatus which is shown connected at 18.

In Figure 2 use is made of a metallic 45 sim-plexed telephone line shown at 13 by bridging small condensers 15 across the metallic line wires and tapping the middle point for a multiplex circuit. The capacities of the condensers are of a small value so that there is 50 no apparent loss of transmission and disturbing noises cannot be heard in the metallic telephone line, since the condensers are balanced to either line wire by reason of the 55 center connection as shown. From the condensers 15 at the left, a connection is made to single Morse wire 21 which has no intermediate stations cut in it. The telegraph instruments shown at 12 at either end of the 60 single Morse wire have the air choke coils 11 inserted in series with the line wire to prevent disturbances from telegraph operation in the multiplex circuit. 10 is a quadruplex line with the usual instruments connected at 65 12 in series with the air choke coils 11. The

multiplex apparatus is bridged at 66-67 on the telegraph ends and at 68-69 on the telephone, telegraph ends of the circuit; choke coils and condensers being used likewise in Figures 1, 4 and 5.

I have shown various methods of arranging the circuits involving my invention; it being understood, however, that variations or modifications may be made without, however, departing from the spirit of my invention; the invention having been described in terms employed merely as terms of description and not as terms of limitation.

What I claim is:

1. Telephone and telegraph circuits comprising sending and receiving telephone and telegraph apparatus, line circuits, a superimposed circuit on said line circuits involving additional sending and receiving apparatus, air choke coils connected in series between the first mentioned telegraph sending and receiving apparatus and the ends of the telegraph portion of the line circuits, and small capacity condensers connected in series across the line wires of the telephone portion of said line circuits so as to provide a connection for the super-imposed circuit to the telephone portion of the circuits of equal capacity to both sides of said line wires of the telephone portion of the line circuits.

2. Telephone and telegraph circuits comprising sending and receiving apparatus, line circuits, a superimposed high frequency circuit on said line circuits involving additional sending and receiving apparatus, air choke coils connected in series between the first mentioned telegraph sending and receiving apparatus and the ends of the telegraph portion of the line circuits, and small capacity condensers connected in series between the line wires of said line circuits so as to provide a connection for the superimposed circuit.

JOHN W. COOK.
